(57) CLAIM

The ornamental design for a storage hook, as shown and described.

DESCRIPTION

FIG. 1 is a perspective view of the storage hook according to the principles of the present invention;

FIG. 2 is a front view of the storage hook of FIG. 1;

FIG. 3 is a rear view of the storage hook of FIG. 1;

FIG. 4 is a top view of the storage hook of FIG. 1;

FIG. 5 is a bottom view of the storage hook of FIG. 1;

FIG. 6 is a right side view of the storage hook of FIG. 1;

FIG. 7 is a left side view of the storage hook of FIG. 1; and,

FIG. 8 is a perspective view of the storage hook of FIG. 1 wherein the bull horns are rotated out of the way so that the back plate can be fastened directly to a wall.
